UNITED STATES PATENT OFFICE

2,400,332

SELF-ADJUSTING ELECTRODE SUPPORT

Charles H. Bachman, Scotia, N. Y., assignor to
General Electric Company, a corporation of
New York

Application September 27, 1944, Serial No. 556,023

5 Claims. (Cl. 250—162)

The present invention relates to cathode ray tubes and it has for its object to provide an improved electron lens system for such a tube.

In a cathode ray device, such as an electron microscope in which a visible image is formed by the action of an electron stream, it is customary to use an electrostatic lens system in the form of a plurality of metallic disks axially aligned and spaced, the center disk operating at a different potential from that of the outer ones. One of the problems in the construction of an electron lens of this type is that of maintaining very accurate alignment of the elements and, at the same time, insulating one or more elements from the rest.

It is an object of the present invention to provide an improved insulator means for such an electrostatic lens system.

It is a further object of my invention to provide a new and improved insulator for supporting a removable electrode in an electronic tube which permits easy insertion of the electrode in the insulator and which prevents vibration of the electrode in its insulator support.

The foregoing objects are accomplished in accordance with one embodiment of the invention by providing an insulator in the form of a rod which extends around substantially the entire periphery of the electrode member operating at a high potential with respect to an enclosing envelope and which is grooved at a plurality of points to support the electrode. In addition, the insulator is slotted in at least one point to form a spring-like section which may be deflected to insert the electrode in the grooves in the insulator.

The features which I desire to protect herein are pointed out with particularity in the appended claims. The invention itself may best be understood by reference to the following description taken in connection with the accompanying drawing, in which Fig. 1 shows schematically an electron microscope which includes an electrostatic lens system of the type considered in the present invention, and Fig. 2 is an enlarged end view of the insulator used in my improved lens system.

Referring to Fig. 1, there is shown an electron microscope comprising an elongated vacuum-tight container 1 of a tubular metal construction. At one end of the container there is provided a glass insulator 2 which serves to support an electron source in the form of a filamentary cathode 3. The cathode is surrounded by a tubular metal member 4 which confines the emitted electrons to a narrow beam and is cooperatively posi-

tioned with respect to an apertured electrode 5 which is in contact with the metal envelope 1. The opposite end of the envelope 1 is sealed by a glass window 6. A fluorescent coating forming a viewing screen 7 is placed on the inner surface of the window 6. In the normal use of the apparatus, the envelope 1 and the apertured electrode 5 are maintained at ground potential and the cathode is maintained at a high negative potential, for example, being connected to a potential source represented by the battery 8 so that electrons emitted from the cathode are projected axially of the container with the object of producing a visible image on the fluorescent screen 7.

15 Between the cathode 3 and the image-reproducing screen 7 there is placed an object 9 supported by any suitable supporting means (not shown) and to be trans-radiated by an electron beam, the beam being passed through the object 20 and its passage assuming the characteristics of the object.

In order that the electron beam, after modification in accordance with the structural character of the object under investigation as the beam 25 trans-radiates that object, may be caused to provide an enlarged visible image of the object in accordance with the intended use of the microscope, the beam 10, after passing through the object, is caused to pass through an electron lens system of known character. In the drawing, the lens system is illustrated as of the electrostatic type and comprises a series of three apertured metallic diaphragms numbered 11-13 axially aligned and spaced. The diaphragms or disks 30 are provided, respectively, with central apertures 14, 15, 16 through which is projected the cathode ray beam to be deflected by the electron lens system. To this end, the outer disks 11 and 13 are connected to the positive terminal of the battery 8 by conductive connection with the inner surface of the tube 1, while the central disk 12 is connected to the negative terminal of this battery through a conductor 17 which is brought into the microscope enclosure 1 through an insulating bushing 18. Because of the resultant difference in potential between the diaphragm 12 and the diaphragms 11, 13, lens fields are established between these diaphragms which have the effect of refracting the electron beam in a manner analogous to the refraction of a light beam in an optical lens. Additional lens fields may be employed in an electron microscope where so desired.

The outer disks 11, 13 are machined to fit snugly within the envelope 1. The center electrode 12 is supported by an insulator 19 to be described

more fully in connection with the discussion of Fig. 2. In assembly of the electron lens system within the envelope 1, a pair of cylindrical spacers 20, 21 are interposed, respectively, between the disk 11 and the insulator 19 and the insulator 19 and the disk 13.

Means are provided for optical magnification of the image formed on the fluorescent screen 7 and this means is represented conventionally as an optical lens 22 through which the beam of visible radiation 23, projected through window 6 from fluorescent screen 7, is caused to pass.

Where it is desired to operate the electrode 12 at very high potential with respect to the remaining parts of the electron system, the surface and volume leakage of the insulating means employed must be considered. One manner in which the insulating path may be increased, while the insulating area is reduced, is illustrated in the enlarged view of insulator 19 shown in Fig. 2, in which the rod-like insulator 19 is formed of a suitable insulating material, such as porcelain, Micalex, or of a vitreous material, such as Pyrex. The member 19 extends about substantially the entire periphery of the lens member 12 and is bent into a shape such that it contacts the envelope 1 and lens member 12 at a plurality of spaced points 24 on lens 12 and points 25 on envelope 1. The portions of the insulator member 19 adjacent the points 24 are grooved to engage the outer edge of the lens member or electrode 12, while the insulator 19 is machined at the points 25 to conform to the inner diameter of the envelope 1.

In manufacturing the insulator, the rod-like member 19 is formed of a slightly larger outside diameter and a slightly smaller inside diameter than is normally desired. The insulator may then be held to a face plate using three holes 26 drilled through the insulator adjacent the points 24 as means to support the insulator on such a face plate. The grooves 24 are then ground in the insulator and the surfaces 25 are similarly prepared as by grinding. After the insulator is thus shaped as to inner and outer diameters and as to thickness, it is removed from the face plate and a narrow blade saw is used to cut slots 27 through the holes 26 and parallel to the sides of the insulator. Likewise, a narrow slot 28 is cut through one of the contact points 25. Alternatively, the slots may be molded in the original insulator blank.

In the use of the insulator, the slots 27 provide means for permitting easy insertion of the lens 12 in the grooves at points 24. The slot 28 permits decreasing the outer diameter of the insulator to permit easy insertion within the envelope 19. During such insertion of the lens structure in the envelope, arms 29 formed by the slots 27 act as springs which facilitate insertion of the lens in the envelope.

One of the advantages of my improved insulator is that the spring arms 29 of the insulator take up any wear which would ordinarily cause looseness of the lens electrode. Such looseness is obviously undesirable, since it allows vibration of the center electrode of the lens and also

permits the electrode to locate in off center positions causing aberrations of the lens system. Another advantage is the long length of the insulator between the electrode 12 and the envelope 1 which permits operation of the electrode 12 at increased potentials over those which are normally permitted.

The invention described herein may be used to advantage in cathode ray devices or in other 10 types of electronic tubes for supporting an electrode. Numerous additional modifications may obviously be made to my invention and I aim in the appended claims to cover all such modifications at come within the true spirit and scope 15 of my invention.

What I claim as new and desire to secure by Letters Patent of the United States is:

1. In an electronic tube having a metallic envelope and a metallic electrode maintained at a substantial voltage with respect to said envelope, an insulator for supporting said electrode within said envelope comprising a rod forming a substantially closed loop engaging said electrode and said envelope at a plurality of spaced 20 points, said rod being grooved at its points of engagement with said electrode and having a longitudinal slot at one of said points to permit insertion of said electrode in said grooves.

2. In an electronic tube have a metallic envelope and a metallic electrode maintained at a substantial voltage with respect to said envelope, an insulator for supporting said electrode within said envelope having a central aperture for receiving said electrode, said insulator having a 30 plurality of flexible arms adjacent said aperture adapted to engage the outer edge of said electrode to prevent vibration of said electrode.

3. In an electronic tube having a metallic envelope and a metallic electrode maintained at a substantial voltage with respect to said envelope, an insulator interposed between said electrode and said envelope, said insulator being grooved at its point of engagement with said electrode and being provided with a resilient arm near 40 said point of engagement to facilitate insertion of said electrode in said grooves.

4. In a cathode ray tube having a metallic envelope and a centrally apertured metallic disk-like lens member maintained at a substantial voltage with respect to said envelope, an insulator for supporting said lens member within said envelope comprising a rod member extending around substantially the entire periphery of said lens member and contacting said envelope and said lens member at a plurality of spaced points, said member being grooved at said points and said member having a longitudinal slot to permit flexing of said member and insertion of said electrode in said grooves.

5. A self-adjusting support for an electrode comprising a member having a central aperture provided with a groove for receiving said electrode, said member being provided with a slot parallel with said grooved portion for increasing the diameter of said aperture to permit insertion of said electrode in said grooves.

CHARLES H. BACHMAN.
